Geo. E. Clegg

His ATTORNEY.

UNITED STATES PATENT OFFICE.

HARRY B. HILLS, OF TOMPKINSVILLE, NEW YORK, ASSIGNOR TO STEWARD DAVIT & EQUIPMENT CORPORATION, OF NEW YORK, N. Y., A CORPORATION OF NEW YORK.

SHIP'S DAVIT.

1,351,571.

Specification of Letters Patent. Patented Aug. 31, 1920.

Application filed June 30, 1920. Serial No. 392,998.

To all whom it may concern:

Be it known that I, HARRY B. HILLS, a citizen of the United States, residing at Tompkinsville, in the county of Richmond 5 and State of New York, have invented certain new and useful Improvements in Ships' Davits, of which the following is a specification.

My invention relates to ships' davits and 10 it has for its object to connect the crank to the operating screw moving the boom in-board and out-board, so that when the crank is not in use it can be moved to a position which is out of the way, and still be connected with the operating screw.

I will describe a ship's davit embodying my invention and then point out the novel features in a claim.

In the accompanying drawing, Figure 1 20 is a side elevation of a ship's davit with a crank connected with the operating screw thereof in accordance with my invention. Fig. 2 is a detail view but drawn to a larger scale of the crank and its connection and 25 embodying my invention. Fig. 3 is a detail view of the device shown in Fig. 2 but in a plane at right angles thereto. Figs. 4 and 5 are cross sectional views taken on the lines 4—4 and 5—5 of Fig. 2.

30 Similar reference characters designate corresponding parts in all of the figures.

A type of ship's davit to which my invention is applicable, and parts of which are shown in Fig. 1, is shown in U. S. Patents 35 Nos. 1,123,132 and 1,245,752 granted to T. H. Martin, December 24, 1914, and November 6, 1917 respectively, to which reference for further details of construction and operation may be had.

40 Referring to the drawings, 1 designates a suitable frame or support; 2 a boom or crane; 3 a truck or carriage movable on the frame and on which the boom 2 is pivotally mounted; 4 an operating member, here 45 shown as a screw for moving the truck 3 to

and fro on the frame, and 5 a crank which is connected with the screw 4 as hereinafter described.

6 designates a socket which is provided with a recess to receive the end of the screw 4 and in which it is held by a bolt and nut 7 (see Fig. 4). It is also provided with a vertically extending passage or recess 8 to receive a portion of the crank 5 and this portion of the crank is retained in the recess or passage by a screw, rivet or other fastening device 9 (see Fig. 5). The socket is further provided with a recess 10 in which the bent end 11 of the crank fits (Figs. 2 and 3) so that reverse motions may be imparted to the screw 4 through the crank 5 and socket 6. A pin 11^a removably held in ears 11^b carried by the socket 6 may be employed if necessary to hold the end 11 in the recess 10 (see Figs. 2 and 3). The socket is also provided 55 with a recess 12, at right angles to the recess 10 in which the end 11 of the crank fits when the crank is not in use. The end 11 is made to occupy this recess by raising the crank in the socket (see dotted lines Fig. 2), 60 turning the crank 90 degrees, and then lowering the end 11 into the recess 12 as shown in dotted lines in Figs. 1 and 2. In this position the crank is out of the way but is still connected with the screw, and ready for use 65 by reversing the operation just described.

What I claim as my invention is:

In a ship's davit in combination with the boom, an operating screw, a crank, and a connection between the crank and screw 80 comprising a socket fixed to the screw in which the crank is vertically movable, and said socket being provided with two recesses in either of which the end of the crank may be placed.

HARRY B. HILLS.
